UNITED STATES PATENT OFFICE.

LEONARD LOOP, OF TULSA, OKLAHOMA.

SAFETY HOOK.

1,416,961.

Specification of Letters Patent. Patented May 23, 1922.

Application filed December 22, 1921. Serial No. 524,265.

To all whom it may concern:

Be it known that I, LEONARD LOOP, a citizen of the United States, residing at Tulsa, in the county of Tulsa and State of Oklahoma, have invented a new and useful Safety Hook, of which the following is a specification.

This invention relates to safety hooks, and more particularly to a hook especially designed for lifting sucker rods, tubing or the like.

The primary object of the invention is to provide a hook of this character which will be locked to the tubing or sucker rod in a manner to prevent the same from falling from the hook should slack occur in the hoisting line.

Another object of the invention is to provide manually operated means for releasing the hook when it is desired to disengage the hook and article lifted thereby.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a side elevational view of a hook constructed in accordance with the present invention.

Figure 2 is an elevational view of the hook, disclosing one of the side edges thereof.

Figure 3 is a sectional view taken on line 40 3—3 of Figure 2.

Referring to the drawing in detail, the hook embodies a body portion 5 formed with opposed arms 6 and 7 respectively, the arm 6 being cut away as at 8 to accommodate one 45 end of the pivoted latch member 9. This latch member 9 is secured within the cut away portion 8 as by means of the pivot pin 10, whereby the latch member may swing laterally, allowing the bail of a section of 50 well tubing to pass between the arms, to secure the hook.

The arm 7 is also formed with a cut out portion indicated at 11 providing a clearance for the free end of the latch member 9 as 55 clearly shown by Figure 3 of the drawing. The cut out portion 11 is relatively long as

compared with the cut away portion 8 to accommodate the locking arm 12 which has pivotal connection with the arm 7, as at 13, the arm 12 operating between the walls of 60 the groove 14 formed along the outer surface of the arm 7.

In order that the locking arm 12 will be normally held in a position to lock the latch member 9 against movement, a spring member 15 is provided, which spring member has one end thereof secured to the body portion 5 as at 16, the opposite end thereof engaging the outer surface of the arm 12. As shown, the intermediate portion of the 70 spring member 15 normally lies in spaced relation with one wall of the arm 7 so that the spring member may be forced downwardly at this point, causing the locking arm 12 to pivot upwardly. It is to be understood 75 however that the outer or free end of the member 15 has connection with the arm 12 as by means of the pins 17.

Supported at one end of the body portion 5 is a pivoted head 18 which is formed with 80 an opening 19 to accommodate the reduced portion 20 of the body portion 5, the outer end of the reduced portion 20 being formed into a head 21 to secure the head 18 to the body portion 5. It might be further stated, 85 that the outer ends of the arms 6 and 7 are curved as at 22 to guide the hook to the article to be lifted.

Having thus described the invention, what is claimed as new is:—

In a hook, a body portion including opposed arms, a latch member supported by one of the arms, the opposite arm having an opening to accommodate the free end of the latch member, a locking arm adapted to normally lie in the path of travel of the latch member to restrict movement thereof, a spring member having one end secured to the locking arm and having its opposite end secured to the body portion, the intermediate portion of the 95 spring lying in spaced relation with the body portion to permit the intermediate portion of the spring to move downwardly, and rock the locking arm upwardly and release the latch member.

In testimony that I claim the foregoing as my own, I have hereto affixed my signature in the presence of two witnesses.

LEONARD LOOP.
